UNITED STATES PATENT OFFICE.

HENRI LAFAGE DE GAILLARD AND MARIE HIPPOLYTE ALEXANDRE PORTRET, OF TOULOUSE, FRANCE.

APPARATUS FOR PREVENTING COLLISION OF TRAINS.

SPECIFICATION forming part of Letters Patent No. 661,513, dated November 13, 1900.

Application filed May 23, 1900. Serial No. 17,734. (No model.)

To all whom it may concern:

Be it known that we, HENRI LAFAGE DE GAILLARD and MARIE HIPPOLYTE ALEXANDRE PORTRET, citizens of the French Republic, residing at Toulouse, Haute-Garonne, France, have invented certain new and useful Improvements in Apparatus for Preventing the Collision of Trains; and we do hereby declare the following to be a full, clear, and exact description of the invention, such as will enable others skilled in the art to which it appertains to make and use the same.

The object of the present invention is a device comprising several series of apparatus to be placed on the ground outside the railway-lines and to be operated when the trains are passing either by a piece fixed to the side bars of the tender or to the locomotive or by the flange of the wheels or by the hand exceptually for the purpose of avoiding the collisions and the running against each other of the trains, the signal of the danger being given to the train-guards.

These apparatus, which are placed in groups and at a distance suitable for the protection of the trains, are connected together by a metallic device, (chain or cable,) insuring the operation of a group of apparatus when a train is passing a preceding group.

In the annexed drawings, which are given as an example, Figure 1 is an elevation of apparatus operated by a device fixed to the tender or to the locomotive. Fig. 1^a is a view in continuation to the right of the mechanism shown in Fig. 1. Fig. 2 is a plan of Fig. 1. Fig. 3 is a section on the line X Y in Fig. 1. Fig. 3^a is a view in continuation to the right of the mechanism shown in Fig. 3. Fig. 4 is an elevation of a device which is operated by the flange of the wheels. Fig. 5 is a plan of Fig. 4. Fig. 6 is a cross-section on the line V V in Fig. 4. Fig. 7 is a cross-section on the line W Z in Fig. 4. Fig. 8 is a diagram of the connection between the apparatus shown in Fig. 1. Fig. 9 is a diagram of the connection between the apparatus shown in Fig. 4.

Each group comprises the apparatus 1 2 and 1^a 2^a. The apparatus 1 and 1^a, which are alike and which are designed to protect the trains which are running in the same direction, consist of a support 1 1^a, upon which is mount-

ed a multiple pulley or striker 3 3^a, movable around an axle and the groove of which serves to receive the operating-chains, the operation of which will be described hereinafter. A 55 fork 4 4^a, with striking branches 5 5^a, is mounted on the supports 1 1^a and indicates whether the line is opened or closed, according to its position relatively to the line.

The apparatus 2 2^a, which are alike and 60 which are used to protect two trains coming toward each other on the same line, are comprising a support 2 2^a, having axles upon which an articulated signal device 6 6^a, a pendulum 7 7^a, and a striker 8 8^a are mounted. 65

The apparatus 1 2 and 1^a 2^a, &c., are forming one group, the distance apart of each group is forming a section.

The pieces which are fixed to the tender or to the locomotive and which are designed to operate the apparatus which are fixed along the line, as well as to warn the attendants of the trains, are the following: The pressing-buffer 9, which acts upon the striker 3 3^a, the articulated ring 10, which has to come over the signal 6 6^a when the latter is in the inclined position shown in the apparatus 2^a, and the hurter 11, which hurts against the forks 4 4^a. Let us suppose that a train is running in the direction of the arrow N, Fig. 1. The striking 70 pulley 3 receives from the buffer 9, fixed to the tender, a pressure upon its upper part, which causes it to turn while causing the operation, first, of the fork 4 by means of the chain i, fixed to the fork 4 by the arm 12 of the fork and 75 which runs over the grooved pulley 13 and passes over the small diameter of the pulley 3, the fork 4 thus being brought across the line and closing the same—that is to say, if a second train should follow the first one it 80 would knock against the fork 4 by means of the hurter 11 while giving a sound-signal to the attendants of the train—and, second, of the apparatus 2^a, which is placed at the distance 85 of two sections. In fact, when the pulley 3 is turning it exerts a traction on the chain j, fixed to the pendulum 7^a, and the latter is thus 90 caused to incline and moves the hurter 8^a, with which it is connected and which, being brought to stop under the said pendulum, 95 keeps the same in the inclined position. At 100 the same time the signal 6^a is inclining by its

own weight. As its lower branch is heavier than its upper branch, it comes to rest upon the inclined pendulum and presents a sharp angle in the direction opposed to the running of the first train. Therefore if a train was directed on the same line as the first one, but in an opposite direction, the ring 10, with which it is provided, would remain hanging in the signal 6^a while producing a disconnection which would insure the operation of an alarm-bell. The ring 10, which is hanging from the square rod 14, may be separated therefrom at the time it is caught, the latter being ended by two spring-blades 15, upon which is clamped the collar 16 of the ring 10, Fig. 3. Thus no danger of breakage is to be feared. In continuing its way ahead the first train will pass freely over the signal 6^a, which will be tilted by the pressure of the ring 10 without the latter being caught and will again resume its inclined position under the action of its lower arm, which thus forms a counter-weight. It is therefore necessary that the train, the running of which we are following, after having protected itself rearward and forward makes the line clear behind itself after having passed the zone of protection. The arrangement of the apparatus 1 and 2 enables the pieces 9, 10, and 11 to operate this.

Let us consider the two groups of apparatus 1 2 and 1^a 2^a, Figs. 1 and 2, which are connected together. In order that the line be cleared after the passage of the first train, the fork 4 must have been brought in parallel with the line and the signal 6^a must again be horizontal. To this end when the buffer 9 hurts the pulley 3^a the latter turns, exerting upon the chain 1^a a traction, the effect of which will be to put the hurter 8^a straight again and to bring the pendulum 7^a into the vertical position again, (both the pendulum and the hurter being connected together by a chain,) while the signal 6^a will again be brought horizontally; but the pendulum 7^a is connected to the striking pulley 3 of the apparatus 1 by the principal chain *j*, to which is fixed a secondary chain *x*, rolling up upon the pulley 3 in an opposite direction to the chain *j*, so that this chain *x* acts by traction and causes the pulley 3 to rotate, thus operating the chain *i*, and, further, it brings the fork 4 parallel to the line, while its lower branch 5 hurts against the stop 17. During this rotation of the pulley 3 the portion of the chain *j* which is comprised between the apparatus 1 and the guide-pulley 18 will cease to be stretched and will not act. The chain *x* passes through a ring 19, fixed at proximity of the apparatus 2, which serves as a stop-point to limit the stroke of this chain, which has a spherical link. The position of the stop-point on the line depends from the stroke of the chain *x* and from the distance apart of the groups of apparatus. The adjunction of the chains *x* *x*^a is necessary, because if the chain *j* had to operate by itself it would op-

erate on both the signal 6 and the fork 4 and the section would remain closed instead of being cleared.

The operation of each of the groups of apparatus would be the same if the first train was supposed to run in the direction of the arrow S, Fig. 1.

The apparatus 2 and 2^a are provided with a device which secures the operation of the signal 6 6^a in case the chains should break or fail to act. To this end a relief-chain *m* *m*^a is secured to the main chain *j*, which passes over a pulley 20 20^a and which supports a counterweight 21 21^a, so that if the chain should happen to break these counterweights when falling would operate the signals 6 6^a independently and would be enabled to strike at the same time an electric contact-push in order to warn the attendants of any stationary post.

In some particular cases the whole apparatus could be operated by hand by means of a lever 22 22^a, fixed on the shaft of the pulleys 3 3^a, instead of being operated by a buffer, or it could also be operated by the flange of the wheels of the locomotive, the said flange operating a pedal having a determined position along the line, Figs. 4 to 7. In this device a piece 23, which might itself assume a vertical position, is acting as a pedal. It projects beyond the inner side of the rails a few centimeters and is able to oscillate freely around its axle, which is supported by a bearing 24. When a train is passing, the piece 23 is being hurt by the flange of the wheels, and by inclining it transmits the shock to either one of the cams 25, mounted upon the shafts 26, which turn in bearings 24 and 27. While turning, the shaft 26 causes the levers 28 and 29, to which it is connected, to operate. On several points of the lever 28 there may be attached a chain *t*, made fast around a pulley 30 on the shafts 3 3^a of the apparatus 1 and 1^a. When a train is passing by, the lever 28 describes an arc of a circle and carries along with it the chain *t*, the traction of which causes the pulley 3 to turn and to operate the chains *i* *j* *l*, as hereinbefore described.

A counterweight 31, fixed on the lever 29, allows of the pieces of the mechanism to resume their first position after the passage of the train, but without operating directly the apparatus 1 and 2. The piece 23 resumes itself its vertical position when the train has passed.

The pedal device is a double one and has to be operated by the passage of the trains in both directions on the same line and has to make the line clear when leaving each section, as this is done by the buffer.

Fig. 8 shows the diagram of the device for interposing apparatus operated by the buffer—viz., the way they are placed and arranged together along the railway-lines. As seen in that figure, the apparatus 1 and 2 of the group I instead of being connected to

the apparatus 2^a and 1^a of the group II, which follows immediately, are only connected to those of the group III, then those of the group II to those of the group IV, those of the group III to those of the group V, and so on. In this way the zone of protection comprises a section in addition to that in which the running train has entered.

Fig. 9 shows the device for interposing the pedal device, which is constructed on the same principle as that shown in Fig. 8, with the addition of the pedal 23.

We claim—

1. In an apparatus for preventing the collision of railway-trains, the combination of a striking pulley mounted on a horizontal shaft in bearings at the side of the track and carrying the pulley of smaller diameter, a horizontal fork pivoted to a fixed foundation adjacent to the pulley and adapted to swing across the rail, and a chain or cable around and secured to the smaller diameter pulley at one end and to the fork at the other, the striking pulley being located in the path of the movement of some part of the train, substantially as described.

2. In an apparatus for preventing the collision of railway-trains, the combination with two similar devices located alongside the tracks at a distance apart, each comprising a vertical striking pulley, a horizontal shaft upon which it is supported, mounted in fixed bearings at the side of the track, a second pulley carried by the shaft, a horizontal fork mounted on a vertical pivot and adapted to

swing across the track, and a chain or pulley connecting the second pulley with the fork, the two striking pulleys being located in position to be successively struck and rotated by the moving train, the two similar devices being connected for conjoint operation substantially as described.

3. In an apparatus for preventing the collision of railway-trains, the combination of a horizontal shaft mounted in bearings at the side of the track, a striking pulley thereon in the path of some part of the train, a pivoted counterbalance-signal in advance of said pulley, a pendulum pivoted adjacent to the signal, and a chain connecting the striking pulley and the pendulum, substantially as described.

4. In an apparatus for preventing the collision of railway-trains, the combination with a striking pulley pivoted at the side of the track, a horizontal pivoted fork adjacent to the striking pulley, a chain connecting the striking pulley and fork, a pivoted counterbalance-signal adjacent to the pulley and fork, a pendulum under the signal, and a chain connecting the pendulum with the striking pulley, substantially as described.

In testimony whereof we affix our signatures in presence of two witnesses.
